SHROUD FOR CASSETTE-TYPE TAPE DECK OR THE LIKE

Vincent L. Jacques, Longmont, Ted F. Kelley, Jr.,
Boulder, Ernest P. Kollar, Broomfield, and James M.
Tagawa, Boulder, Colo., assignors to International
Business Machines Corporation, Armonk, N.Y.

Filed Mar. 30, 1971, Ser. No. 129,498

Term of patent 14 years

Int. Cl. D14—01
U.S. Cl. D26—14 B

FIG. 1

FIG. 2

FIG. 1 is a front perspective view of a shroud for a cassette tape deck showing our new design, and

FIG. 2 is a rear perspective view of the design of FIG. 1.
We claim:

The ornamental design for a shroud for cassette-type tape deck or the like, substantially as shown.
